REVERSIBLE FRICTION CLUTCH WRENCH

Lawrence E. Pratt, Riverdale, Ill.

Application December 13, 1943, Serial No. 514,089

22 Claims. (Cl. 74—157)

1

My invention relates to improvements in reversible friction clutch wrenches and has for objects the provision of a wrench of this type which shall be simple and comparatively easy and cheap to manufacture and which shall be readily usable and manipulated, efficient in operation, capable of withstanding hard usage, and of long life.

A further object is the provision of a friction clutch type of wrench in which there is practically no lost motion in gripping the rotary shank or releasing same.

Another object is the provision of such a wrench having simple and positive reversal means easily operated from the exterior.

Another object is the provision of such a reversible means which is operable without exposing the interior wrench mechanism to the entrance of dirt.

A still further object is the provision of such a wrench in which the interior mechanism is sealed against the entrance of dirt.

Another object is the provision, in such a device, of clutching means at three points preferably equidistant to obtain better centralization and effects.

Another object is the provision, in such a wrench, of clutching rollers in pairs acting between the driving and driven members thereof. Another object is the location of such pairs of clutching rollers in the rotary shank or sprocket of the wrench. And another object is the location of such pairs of clutching rollers in the handle or body part of the wrench.

Further objects and advantages will appear from the detailed description and claims to follow in connection with the accompanying drawings which illustrate several embodiments of my invention by way of illustration and not of limitation, and in which—

Fig. 1 is a plan view of one form of the wrench showing a part of the enclosing structure broken away, the better to show the action of the reversing parts;

Fig. 2 is a similar view with some of the parts in changed positions;

Fig. 3 is a similar view showing the parts reversed;

Fig. 4 is a cross-section of the wrench body on the line 4—4 of Fig. 1;

Fig. 5 is a longitudinal cross-section of the wrench on the line 5—5 of Fig. 1;

Fig. 6 is a cross-section on the line 6—6 of Fig. 2, showing the resiliently supported locking ball of the reversing member or selector;

2

Fig. 7 is an exploded view of the wrench showing the parts in perspective;

Fig. 8 is a sectional view of a modification showing a pointed cylinder substituted for the ball in the selector lock or locator;

Fig. 9 is a plan view of another form of wrench having a round body or head and another form of selector lock;

Fig. 10 is a longitudinal central cross-section of the wrench of Fig. 9;

Fig. 11 is a similar view but with the selector lock in withdrawn position;

Fig. 12 is a plan view of a wrench having the clutching rollers in the handle or body part;

Fig. 13 is a cross-section through the head of the wrench on line 13—13 of Fig. 12;

Fig. 14 is a cross-section through a roller slot or recess on line 14—14 of Fig. 12;

Fig. 15 is a perspective view of the reverse selector;

Fig. 16 is a perspective view of the sprocket or nut-socket driver; and

Fig. 17 is a similar view of the spring supports for the rollers.

Referring to these drawings, there are, of course, two main elements in each wrench, the one the handle-body portion by which the wrench is manually manipulated and the other the nut-socket carrying and driving portion, sometimes called the socket driver or rotor, which is rotatably connected to the body portion and projects transversely therefrom to carry a suitable nut socket or spanner. The remainder has to do with the manner of connecting these two elements so that they can be made to act at will in either direction of rotation of the handle as a friction clutch wrench or friction wrench, as it is sometimes termed.

Thus, referring to Figs. 1 to 8, the wrench has

40 a body or ring head 20 and a suitable handle 21 of any desired length by which it may be manipulated, said handle being either separate from the body and secured thereto, as shown in Figs. 1 and 5, or in other desired manner, or it may be 45 integral therewith. The body 20 is provided with a large cylindrical socket, bore or recess 22 (Fig. 7), the periphery of which forms a ring clutching surface and within which the rotor sprocket or socket driver 23 and the clutching parts of the wrench are located.

The socket-driving portion includes a circular end, rotor or sprocket 23 (Fig. 7) having a free turning fit, like a shaft in its bearing, in the socket 22 and having a circular stem, shaft or 50 shank portion 24 which extends through a cor-

responding hole in the bottom of recess or socket 22, and ends in a squared portion 25 to receive the nut-socket 26 (Fig. 5).

In order to permit this sprocket or socket driver 23 to turn in the recess or socket 22 of the handle-body portion or to be gripped or clutched to the surrounding circular ring clutching surface thereof, the periphery of the same is provided with a plurality of recesses 27, preferably three, having inclined bottoms or floors shallower at the centers of the recesses and deeper at the ends and forming inclined clutching surfaces opposed to the said ring clutching surface which surrounds all these recesses.

In each end of each of these recesses a clutch roller 28 having a free bodily movement is placed. The inclined recesses 27 are deeper at their outer ends from the ring clutching surface than the diameters of the rollers 28 and less than their diameters toward their centers. If, therefore, the rollers are toward the ends of the recesses, the socket-driving member or sprocket is free to turn with respect to the handle or body, or the handle or body with respect to the member or sprocket, and when the rollers approach the centers they bind between the inclined bottoms or floors of the recesses and the inside surface of the clutch ring, to thereby cause the handle and body to grip the member and turn the nut-socket.

The rollers 28 are normally bodily spring-pressed toward the shallower parts of the recesses. This is done by short coiled springs 30 passing freely through suitable holes in the sprocket from recess to recess and bearing at their ends against the rollers 28 about midway of their length in adjacent recesses.

With nothing to restrain them, these rollers 28 would thus be urged toward the shallower parts of the recesses and block the handle from turning in either direction. So means is provided to block off at one time one corresponding roller of each set while giving the other roller free rein, whereby the handle may be freely rotated in one direction without turning the socket, but grips it firmly for turning in the other direction. Then by making this means to be adjusted to operate in either direction, that is, on one or the other roller of each set, the wrench may be reversed at will for use with equal facility and effect in either direction.

This reversing means comprises the selector disc 31 having three depending prongs, pins or fingers 32 at the periphery. This selector is adapted to be pushed down over the assembled sprocket 23, rollers 28 and springs 30, with the selector prongs 32 between the rollers of each pair in the recesses and with the disc part thereof preferably lying flatwise at the top of the sprocket 23. This position of the selector prongs 32 is clearly shown in Figs. 1 to 3. By rotating the selector disc 31 slightly relative to sprocket 23 one way or the other, the one roller 28 or the other will be pushed by the finger or prong 32, which is designed to contact the roller outside its center line, into the deeper part of its recess and away from the ring, and therefore cannot bind on the surrounding clutch ring of the body or head of the wrench, while the other roller of each pair on the other side of the finger is free to roll into the shallower part of the recess under pressure of the spring 30 and therefore to clutch, grip and bind between the ring and the floor of its recess when the handle is turned in one direction and to declutch when the handle is turned

in the other direction. This reversal or selector disc 31 and its prongs or fingers do not touch the surrounding clutch ring of the body whereby to avoid any drag tending to undesired reversals.

Since all this mechanism except the protruding shank 24—25 of the sprocket or socket driver is enclosed in the body or head of the completed wrench, means must be provided readily to reverse the wrench, that is, the position and action of these rollers, from the outside. This may be done by temporarily locking the reverse selector 31 from turning within the wrench body and then slightly turning the sprocket 23 by grasping the protruding shank 25 or the nut spanner 26 with the fingers of the hand and slightly turning it. This will have the effect of shifting the sprocket 23 so that eventually the other set of rollers 28 may be engaged by the prongs 32 and moved to the deeper ends of their recesses, out of contact with the clutch ring.

To normally hold the two members 23 and 31, that is, the sprocket and the reverse selector disc, in their proper relative positions when the wrench is adjusted for operation in one direction or the reverse, the member 23 (Fig. 6) is provided with a hole into which a relatively strong spring 33a and ball 33b are placed so that the latter will engage with spring pressure in one or the other of the depressions 33 in the inner face of selector disc 31.

When turning the sprocket 23 by hand in reversal, as above explained, the clutch roller 28 which is being unblocked in each recess soon reaches its clutching point with the ring. This stops further turning of the sprocket, but the construction is such that at this point the ball 33b which has left its seat in one of the depressions 33 has passed over the divide between depressions and is entering the adjacent depression 33. This places the selector disc 31 under spring pressure to be further turned slightly by the ball 33b in finding its seat in the said adjacent depression, when the selector disc shall be unlocked.

The selector disc 31 is now unlocked and, under the influence of the spring 33a and the ball 33b in finding its seat in the depression 33, rotates slightly but sufficiently to complete the reversal. This, of course, is when the other set of rollers 28 is blocked off from clutching position and the first set is freed for clutching operations.

This combination of spring 33a, ball 33b and depressions 33 in connection with the other parts thus has the function of turning the selector disc and its prongs a short distance against the resistance of the springs 30 extending between sets of clutch rollers and the frictional drag of the moving parts. The spring 30 resistance is lessened by the fact that they pass freely through their apertures in the sprocket. However, these parts are designed of a size and strength to carry the load thus imposed thereon.

The ball 33b may be replaced, if preferred, by a pointed pin or cylinder 33c, as shown in Fig. 8, the pin or cylinder sliding and being supported laterally in its aperture, and a suitable spring being seated in the aperture and pressing against the pin. The pin is suitably pointed to engage in the depressions 33 and to have its required action.

The temporary locking means for the reversal selector disc 31 consists of the locking pin 34 located in a suitable bore and recess in the body 20 toward the handle end and adjacent the main socket 22 therein, said pin reciprocating in the plane of the disc 31. The peripheral edge of

the disc 31 is provided with small teeth or notches partially or entirely around the same, and is adapted to be locked from turning by said pin 34 engaging the same. The end of this pin is provided with one or more teeth thus to engage and lock the disc 31 from turning. The periphery of the disc may, of course, be formed with shallow holes, or be knurled or otherwise roughened in place of the teeth or notches, and the contact end of pin 34 be properly formed to correspond respectively with such roughened surface.

This locking pin 34 is moved back and forth by an eccentric pin 35 on the end of a threaded screw 36. A threaded bore 37 intersects the inner end of the bore 38 for the locking pin 34. The latter may be formed by inserting a drill through a hole (Fig. 5) in the outer end of the body 20 and thereafter plugging up the hole by metallic plug 39. When the screw 36 is threaded into its bore 37 the eccentric pin 35 should enter the hole in the end of locking pin 34. This can be done readily before the other parts are inserted in the main socket 22 of the body with the assistance of the pointed end of eccentric pin 35 and the bevelled or reamed-out mouth of the hole in locking pin 34 (Fig. 5). By turning the screw 36 the pin 34 is caused to engage the edge of disc 31 and thereby to lock it from turning in the body. It is unlocked by the reverse movement. This pin 34 is preferably notched or cut away at its upper forward end to be sure not to engage the threaded edge of the cap 47 when projected forward to lock disc 31.

This screw 36 should be readily turnable, since it is used at every reversal of the wrench. It is therefore provided with a disc-like head 40 of substantial size, knurled, if desired, on its edge and with portions cut away to form a tongue or tang 41 for finger operation, as shown in dotted lines in Figs. 1 to 3. This head 40 is designed to fit snugly against the under face of the wrench body when it is turned home fully, which should be substantially at the central position of the tang 41, as shown in Fig. 1, in which position the locking pin 34 is fully retracted so as not to engage the edge of reversal selector disc 31. In this position, too, a holding ball 41a spring-pressed in the body 20 engages in a suitable depression 42 in the inner face of disc 40. This assists in again centralizing the tang 41 when it has been moved therefrom and returned and in resiliently holding it there to insure no undesired locking of the reversal disc 31.

A metal thrust washer 43 and a leather seal or similar washer 44 are placed on the shank 24. The sealing washer 44 has a hole preferably slightly smaller than the shank 24 so as to fit snugly thereagainst to provide an effective seal around said shank. The metal washer 43 provides a bearing over the whole surface of the sealing washer 44 to press and seal it against the bottom of the socket 22, and its upper surface closes the bottoms of the roller recesses in the periphery of the sprocket to keep the rollers 28 in place in the use of the wrench and is of advantage in assembling.

When the parts are otherwise assembled in the body a centering and thrust pin 45 is inserted, with its small diameter end fitting into a corresponding hole in the center of sprocket or socket driver 23, its larger part above fitting in the central opening of reversal disc 31 (Figs. 5 and 7). The portion of the pin passing through the disc 31 is a few thousandths of an inch longer

than the thickness of the disc 31, so that the top disc or enlarged head of the pin 45 does not bind on the surface of the disc 31 when pressure is applied to the pin. A ball seat is formed in the top face of the pin and a bearing ball 46 is placed therein. This centralizes the rearward or inward thrust of the sprocket or rotor practically to a point and reduces the friction due to rotation to a minimum. It also definitely spaces the parts apart. A screw cap 47, having a groove or kerf in the outer face for a screwdriver blade or similar tool, is then threaded into the open end of said main receptacle or socket 22 and down onto the ball 46. This cap 47 should be adjusted to take all play out of the assembly and still leave it free to operate properly. Thus the reversing disc 31 is accurately centered and kept from engaging or dragging on the wall of the socket 22 and is free to rotate on the sprocket 23 despite pressure that may be applied by cap 47 through ball 46 to the head of pin 45. The rollers 28 are likewise free to move when the parts are so clamped together.

When finally adjusted a locking screw 48 (Fig. 4) may be inserted to engage the edge of cap 47 and lock it.

The nut-socket 26 is held onto shank 25 by a ball 49 spring-pressed outwardly and held in its socket in shank 25 in any desired way, but conveniently by center punching or swedging the material of the shank near the edge of the hole over the ball. In operation, the turning of the wrench handle clockwise or right-handedly, with the parts as shown in Fig. 1, will cause the free rollers to grip or wedge between the member 23 and the surrounding circular wall of the socket 22 in the body, and thus turn or drive the wrench socket. And when the handle is reversed the rollers 28 tend to roll toward the larger ends of their recesses and free the handle so it can be turned back without rotating the sprocket and the wrench socket. The dimensions are such that such engagement and disengagement of the rollers take place almost instantly, so that there is practically no lost motion.

When it is desired to reverse the action of the wrench, the selector disc 31 with its prongs 32 must be shifted relatively to the sprocket or socket driver 23 to confine the other set of rollers to their end positions in the sprocket recesses and free the set which had just been confined. This is the position of Fig. 3. This, briefly, is accomplished by turning the finger-piece 41 of cap 49 of screw 36 from the position in dotted lines, 55 Fig. 1, to that of Figs. 2 and 3. This locks, by pin 34, the selector disc 31 with its prongs 32 to the body 20 of the wrench. Now grip the body or handle of the wrench in one hand. With the other turn the shank 25 slightly—as far as possible—in the opposite direction from that you want the wrench to drive it. Then take the hand away from the shank or socket and with it release the selector lock 41, moving it back to its central position of Fig. 1. The spring 33a, ball 33b and depression 33 now come into play and move the unlocked selector disc 31 and its prongs 32 the remaining distance to complete the reversal. In this operation of reversing, the nut-socket 26 or shank 25 should, of course, be turned by the fingers of the hand in the same direction it had been turning just before when operated by the wrench handle, or, as explained, in the opposite direction from that the wrench is intended to drive it.

It will be seen from the foregoing that the

wrench is sealed from all dirt from the outside. By threading the screw 36 into its aperture a seal is provided to prevent dirt from entering the clutch part of the wrench at this point. Even the turning of the same to lock the reversal selector 31 is in a direction to unscrew the same and therefore does not carry dirt into the interior of the wrench; and turning it in the reverse direction only turns in the clean threads, so no dirt is carried in. The leather washer 44 provides a seal against the entry of dirt between the sprocket 23 and the body 20 and around the shank 24, and the threading of the cap 47 into the open end of socket 22 stops dirt from entering there. The plug 39, preferably permanently secured in position, seals the opening used for drilling the bore for locking pin 34. Since these are the only points at which dirt might otherwise enter, it is entirely excluded. This is important in such a wrench as this, where the rollers and their clutching surfaces must be kept scrupulously free of foreign matter for proper and satisfactory working, and the wrenches are apt to be used in the grimiest of places. Of course the parts should be suitably oiled; in fact, the same may be flooded with oil, and the sealing keeps the same in as well as the dirt out.

This wrench, moreover, is sturdy and strong. The handle 21, as before stated, may be an integral forging with the body 20, and may be of any suitable length to give the desired leverage.

Another wrench, having the advantages of a reversible friction clutch wrench, of long life, simplicity of manufacture and assembly, and in which the working parts are in a sealed chamber free from all dirt and foreign matter, is illustrated in Figs. 9 to 11.

In this form of wrench, the greater part of the interior mechanism of the head or body is substantially the same as in the other form of wrench described, and is so shown. The same reference characters are therefore used as to these parts so far as they may apply.

The main difference here is in the handle, body and the reverse selector lock.

The handle comprises an outer sleeve member 60, preferably of metal, on a shaft, bar or shank member 61 terminating in body portion 62 in which the bore, socket or recess 22 is formed.

In this recess are located the rotating socket driver or sprocket 23 and associated parts of the other form, which operate in the same way and perform the same functions and are designated by the same reference characters.

The temporary locking of the reversal selector 31 for the purpose of reversing the action of the wrench is accomplished by the rod 63, which passes longitudinally through the handle member 61 and has a forward pointed or otherwise suitably shaped end 64 adapted to be projected between the teeth on the periphery of the selector disc 31 or against the said edge of the disc in a way to lock the same against turning or rotating in the socket 22.

In order so to project the locking rod 63 into locking engagement with disc 31 the handle sleeve member 60 extends beyond the end of the shank member 61, leaving a small space therein into which the locking rod 63 extends. On its end within the said space a press-fitted thrust bushing 64 is located. This bears against the inside end of the handle sleeve portion 60 and by said sleeve the rod 63 may be projected forward to cause its end 64 to engage the selector disc 31.

A packing 65, such as a felt washer, is com-

pressed around the rod 63 within said end space to prevent any foreign matter that may work into the handle from working its way up into the body or head of the wrench. A metal washer 66 forming a seat for the inner end of a coil spring 67 on the rod and extending between the end thrust bearing 64 and spring seat washer 66 keeps said packing washer 65 compressed against the rod and handle end. The inner face of this washer 66 is preferably concaved or outwardly flaring, the better to compress the felt or similar washer 65 about the rod 63 and on its seat.

The spring 67 resiliently pushes the handle member 60 and the rod outwardly into an unlocking position of the tapered end 64 of the rod, or in other words out of contact with disc 31.

The handle member 60 is prevented from moving only far enough to unlock the disc 31, by a slot and screw 68, the latter threading into the handle member 61 and its head flush with or a little below the outer surface of handle sleeve 60 moving in the slot therefor in the sleeve 60.

In this form the centering and thrust pin 45a has an enlarged head 45b which may be nearly as large in diameter as the selector disc 31, if desired, and with a deeper edge flange than the thickness of the remainder of the disc forming the head 45b, or it may be hollowed out or concaved a few thousandths of an inch in any desired way on the under side between the central stem and the periphery, so that only the periphery of the head 45b will contact or stand close to the outer face of disc 31.

Here again the portion of the pin 45a passing through the selector disc 31 is a few thousandths of an inch longer than the thickness of the disc, so that the disc 31 is free to turn despite the clamping pressure on the pin and parts which are centered on the ball 46 and transmitted to the cap 47. However, the action of the spring 33a on the locking ball has a tendency, in pushing upwardly or outwardly on the under side of the selector disc 31 at the ball seats 33, to tilt the disc and cause it slightly to tend to bind on the pin 45a. But by having the contact surfaces of the head of the pin 45a and the outer face of the disc 31 at or near their peripheral edges, such binding tendency will be reduced.

In order to reverse the operation of this wrench, the handle is pushed toward the body or head of the wrench. The tapered end 64 of the rod 63 is caused to engage in one of the notches in the selector disc or head, as in Fig. 10. Then while holding it so locked, with the other hand turn the shank 25 and sprocket 23 in a direction opposite that it is desired for the wrench to operate, until the shank is stopped. This will cause the ball to compress its spring 33a and leave one of the recesses 33 and seek the other. Now release the handle 60. Spring 67 therein will cause the rod 63 to disengage and unlock the selector disc 31. The spring 33a will then snap the disc 31 and its prongs 32 around to their final position by the seating of the ball in the sought depression 33, thus completing the reversal of the wrench.

While in this form of wrench, in such reversal, the locking pin must be held pressed forwardly to lock the selector disc to the body until the sprocket has been turned, it is most conveniently done by pressing the head of the wrench against any near-by object until the sprocket is turned by grasping the shank 25 or the nut-socket 26 and slightly turning it until stopped. This would

all be done in much less time than it takes to tell it.

Or, if the user wanted to reverse the wrench while the socket was still engaging the nut, as in backing the nut off a trifle from its set position, he could press forwardly on the handle and swing it slightly and lightly in the right direction until stopped, to effect the same turning of the sprocket relatively to the locked selector disc as before, though in this instance he would be turning the selector instead of the sprocket. Then by releasing the longitudinal pressure on the handle the selector would be unlocked from the body and the spring ball would complete the turning of the selector disc as before, to complete the reversal. This also could all be done almost instantly.

This form of wrench of Figs. 9, 10 and 11, with its narrower body portion near the circular body portion, may be used in certain close places where possibly the other form with its tapering body could not, for lack of room.

In the wrench of Figs. 12 to 17, the clutch rollers are located in the body or ring of the wrench and clutchingly engage the cylindrical end of the sprocket or socket driver for wrench operation. Thus, as shown, the clutch rollers 10 are located in pairs in slots 71 formed in the body or ring 72 at the head end of the wrench in tangential relation to the hole or socket 73 therethrough for the cylindrical end of the sprocket or nut-socket driver 74, Fig. 16, and preferably at 120° apart around said socket. The slots or recesses 71 for the rollers are close enough to the central hole 73 so that the circular end of the sprocket or socket driver 74 which fits and rotates in said hole projects slightly into the slots, as indicated, and is clutchingly engaged by the rollers 10 when the latter are moved toward the centers of the slots, such clutching being between the floors of the slots and the cylindrical end 74.

The clutch rollers 10 are resiliently pressed toward the centers of the slots and the end of the socket driver by coil springs 75 bearing against them about midway of their length. These springs are maintained in position by being mounted on studs 76 secured to and projecting from plates 77 (Fig. 17) fitting into and against the ends of the slots 71.

The reverse selector for the rollers in this instance consists of the disc-like member 78 (Fig. 15) carrying selector pins or prongs 79 press-fitted thereto and extending between the rollers 10 of the respective pairs, as indicated. By oscillating this selector disc the pins or prongs engage and correspondingly press the corresponding roller of each pair toward and into its end of the slot and out of contact with the sprocket or socket driver 74, while the other roller of each pair is free to clutchingly engage the sprocket or clutch driver or declutch the same for wrenching operation in the one direction. The line of engagement of the pins with the rollers in each pair is preferably inside the plane of their center lines or axes, whereby to tend to push the rollers away from the sprocket and toward the floors of the slots when they are engaged thereby.

This selector 78 is maintained in position by a circular cap 80 of substantially the diameter of the wrench body or ring 72 and secured solidly thereto by screws 81 preferably three in number passing through apertures 82 in the body 72 and threading into apertures 83 in the cap 80. This

cap is recessed in its inner face to receive the selector disc 78 and is apertured to permit passage of the central cylindrical boss or part 84 of said disc 78. In this way the selector is centered and positioned and is so maintained, yet is permitted to be oscillated for reversal of the wrench. This oscillation is conveniently accomplished by grasping and turning a raised portion 85 extending diametrically across the cylindrical portion 84.

10 A felt or other washer 86 is fitted and pressed into suitable annular recesses in the selector disc and the cap and prevents the entrance of moisture and dirt between these parts.

15 A ball 87 supported by a spring 88 in a hole 89 in the ring 72 engages in suitable seats 90 in the inner face of the selector disc 78 to resiliently hold the selector in its one position or the other.

20 On the opposite side of the body or ring 72 there are secured a metal thrust disc 91, a preferably leather sealing disc 92 and a metal retainer disc 93, all in ring form to accommodate the passage therethrough of the cylindrical extension 94 and the squared end 95 of the sprocket or socket driver 74. The end 95 is adapted to receive and carry the usual nut-socket or similar device, which is held thereon by spring and ball in the usual manner. The leather washer or disc 92 closely fits the cylindrical part 94 of the socket driver and seals against the entrance of dirt around said part as well as between the faces of the thrust washer and clamping ring 93.

25 The screws 81 pass through these plates or rings, as indicated, and, when tightened, serve to clamp and bind all the stationary parts together. The diameter and depth of the depression in cap 80 which holds the selector in position are a little larger than the corresponding dimensions of the selector disc 78, so that when the wrench is assembled and the screws 81 are drawn tight, the selector is still free to be oscillated.

30 The screws 81 pass through these plates or rings, as indicated, and, when tightened, serve to clamp and bind all the stationary parts together. The diameter and depth of the depression in cap 80 which holds the selector in position are a little larger than the corresponding dimensions of the selector disc 78, so that when the wrench is assembled and the screws 81 are drawn tight, the selector is still free to be oscillated.

35 A ball 96 and spring 97 are placed in the center of the head of the sprocket or socket driver 74, which reduce to a minimum the rotational friction between the head 74 and selector 78. The spring 97 keeps the sprocket or socket driver 74 pressed normally against the thrust plate 91, but if the same is pressed back toward the selector 50 78, the ball 96 seats, as at 98, thus preventing the head of the socket driver 74 from coming in contact with the selector plate 78. This seat 98 of ball 96 is of a depth always to cause the ball 96 to extend a little beyond the end of member 74.

55 By this arrangement of the sprocket or socket driver 74, greater tolerances are permissible in the manufacture of the wrench. While the ball 96 is shown off its seat quite a distance, for the sake of clearness, in the actual wrench the distance is not substantially more than .010 or .015

60 of an inch.

65 The length of the rollers 10 is a little less than the thickness of the body of the wrench, so that they may not bind in action when the parts are all clamped solidly together. The end of the sprocket or socket driver 74 has a free fit, so called, like a shaft in its bearing, in the bore 73 of the body of the wrench, thus keeping it centrally located in the finished wrench. The wrench body 72 is provided with a suitable handle

70 99 which, as shown, may be integral therewith. The operation is thought to be obvious. Turning the handle of the wrench clockwise or right-handedly, as seen in Fig. 12, causes the rollers in 75 the trailing ends of the slots to clutch the end

of the socket driver to drive the same and the nut-socket carried thereby in the same direction. Turning the handle back causes the said rollers to be freed from clutching engagement with the sprocket driver and permits the handle to be brought back without turning the nut. To reverse the wrench the cross-member 85 of the selector 78 is turned manually a short distance in the direction the handle is to be turned to drive the nut-socket—in this instance, counter-clockwise or left-handedly. This will bring the pins or prongs 79 against the opposite rollers of the pairs, rendering them inoperative, as explained, and permitting the other roller of each pair to clutch when the handle is turned to the left and to unclutch when the handle is turned to the right, thus giving a left-handed operation to the wrench. In turning the selector from one position to the other, the spring ball 87 passes from one seating recess 90 to the other and resiliently holds the selector in the desired position.

In all forms of the wrench there are preferably three sets of clutching rollers at 120° apart around the clutching surface. This gives a better centralization and equalization of the gripping effects of all the rollers than a greater number under all conditions of use and for all time within the life of the wrench. The wrenches in all these forms are provided with a chambered head which is sealed against the admission of foreign matter to the interior, and the selector mechanism for reversal is operated from the outside without breaking the seal. Pairs of rollers preferably are used for clutching, declutching and reversing.

Having thus described my invention and several embodiments thereof, and appreciating that various changes and alterations may be made therein without departing from the spirit thereof or its scope as set forth in the appended claims, what I claim and desire to secure by Letters Patent is:

1. A reversible friction sealed-chamber wrench comprising a handle and head in the form of a sealed chamber, the latter having a transverse opening therethrough, a relatively rotatable member having a sprocket fitting within the opening and a shank projecting laterally therefrom to carry a nut socket, locking rollers between the circular or ring-like wall of said opening and the seats for the rollers in the sprocket, roller reversing means in the chamber, means in a side opening in the chamber to engage and control the said reversing means and rollers for reversal operation of the wrench, a dirt-excluding washer in the opening around said shank, means for excluding the entrance of dirt to said side opening, and a dirt-excluding cap closing the mouth of said opening over the sprocket, whereby a sealed chamber is formed around the rollers and seats and all dirt is excluded therefrom.

2. A reversible friction wrench comprising a body portion having a transverse circular opening therein, the wall of which opening forms a ring surface, a driven member having a sprocket in said opening having a protruding shank to carry a nut socket and provided with a plurality of equally spaced peripheral recesses, each of which has a surface in the bottom thereof sloping from the shallower central part to the deeper ends and forming, respectively, right-hand and left-hand surfaces opposed to said ring surface, a roller in each end of said peripheral recesses of a size to wedge between said ring and the opposed recess surface when the roller is toward the center of the latter and to free the same when

toward the end of the recess, springs pushing the rollers toward the centers of the recesses, a disc over the sprocket having prongs at the edge extending between the rollers of each pair, said disc being capable of a slight rotation relative to the sprocket to push one or the other of said rollers in each pair toward the end of the recess to convert the wrench from a right-hand to a left-hand wrench and vice versa, a lock operable from the exterior to lock said disc from turning relatively to the sprocket while turning the sprocket slightly by grasping and turning the shank, and resilient means for releasably retaining said disc and sprocket in the one relative position or the other.

3. A reversible friction wrench comprising a handle and a head having a transverse opening therein, a driven nut-socket carrying member having a sprocket in said opening, said sprocket having a plurality of peripheral recesses, a pair of rollers in each said recess, a disc over the sprocket and having peripheral prongs extending between and parallel with the rollers, said disc being rotatable slightly in either direction on the sprocket to render a corresponding roller of each said pair nonlocking, resilient means for releasably retaining said disc in one position or the other on the sprocket, a centering pin extending through the disc and into the sprocket, a ball nested in the outer surface of the head of said pin, and a screw cap threading into and closing said head opening and engaging said ball to hold all parts together and yet free to operate.

4. A reversible friction wrench comprising a handle and a head having a relatively large transverse circular socket therein, the wall of which forms a ring surface, a sprocket fitting into said socket and having a shank extending through the bottom thereof to receive a suitable nut spanner, rollers carried by the sprocket and adapted to engage the said ring surface to cause the sprocket and head to move together when the head is rotated in one direction and to unlock the same when the head is rotated in the other direction, means movable relative to the sprocket to reverse the action of said rollers to enable the wrench to be used in the reverse direction, and means operable from the exterior of the wrench to lock said reversing means to the head whereby said relative movement may be effected by turning the nut socket member or the head while the reversing means is so locked.

5. A reversible friction wrench comprising a handle and head, a rotatable nut-socket carrying member having a sprocket in said head with friction rollers therebetween to enable the same to be operated as a friction wrench, a disc in the head having means by the movement relative to the said sprocket to reverse the direction of operation of said rollers to enable the wrench to be used as a left-hand or right-hand wrench, and means operated from the exterior of the wrench to lock the disc to the head whereby relative movement of the disc and said sprocket may be secured by turning the projecting nut socket when the disc is so locked.

6. A reversible friction wrench comprising a handle and head, a rotatable nut-socket carrying member having a sprocket in said head with friction rollers therebetween to enable the same to be operated as a friction wrench, a disc in the head having means by the movement relative to the sprocket to reverse the direction of operation of said rollers to enable the wrench to be used as a left-hand or right-hand wrench, a locking

pin in the head adapted to engage and lock said disc to the head, a rotatable screw extending transversely from said pin to the exterior of the head, a connection between said screw and pin, whereby the rotation of the screw moves the pin into locking engagement with the disc or withdraws the same, and a finger-piece on the screw at the face of the head to enable the said lock to be readily applied or unlocked, the relative movement between said disc and sprocket to reverse the action of the wrench being caused by turning the nut socket and sprocket when the disc is so locked.

7. A reversible friction wrench comprising a handle and head, a rotatable nut-socket carrying sprocket in said head with friction rollers therebetween to enable the same to be operated as a friction wrench, a disc in the head having means by the movement relative to the said sprocket to reverse the direction of operation of said rollers to enable the wrench to be used as a left-hand or right-hand wrench, a locking pin movable longitudinally in the head toward the periphery of said disc to engage and lock the same from rotation in the head, a threaded screw extending from a face of the head to a point adjacent the opposite end of the pin, an eccentric pin on the end of the screw entering a hole in the end of the locking pin whereby the turning of the screw will advance the pin toward the disc to lock the same or retract it, a disc-like head on said screw engaging the face of the wrench when the screw is screwed home and in the retracted position of the locking pin, the periphery of the disc being notched to leave a finger-piece projecting therefrom, said finger-piece indicating by its position the position of the locking pin, and resilient means for releasably retaining said disc and the locking pin in unlocking position.

8. A reversible friction wrench comprising a handle and a head having a transverse socket therein, a rotatable driven member in said socket having a shank projecting therefrom to carry a nut socket, friction rollers between the driven member and socket wall to lock and unlock the same for wrench operation in one direction, and means to reverse the operation of said rollers to enable the wrench to similarly operate the driven member in the other direction, said means being connected to and controlled by the handle of the wrench.

9. A reversible friction wrench comprising a handle and head, a rotatable nut-socket carrying member having an end in said head with friction rollers therebetween to enable the same to be operated as a friction wrench, a disc in the body having means by the movement relative to the said end to reverse the direction of operation of said rollers to enable the wrench to be used as a left-hand or right-hand wrench, and a lock for said disc operated by the handle to lock the disc to the head, whereby the said relative movement of the disc and said end for reversal purposes may be secured by relatively turning the handle and said nut-socket carrying member while the disc is so locked.

10. A reversible friction wrench comprising a handle and a head having a transverse socket therein, a rotatable nut-socket carrying member having an end in said socket, friction rollers between said end and socket wall to engage and disengage the same for wrench operation, means to reverse the operation of said rollers to enable the wrench to operate in one direction or the other, and a reciprocating rod or pin in said handle

operated by forward pressure on the handle to take part in the reversal operation.

11. A reversible friction wrench comprising a handle and head, a rotatable nut-socket carrying member having an end in said head with friction rollers therebetween to enable the same to be operated as a friction wrench, a disc in the head having means operated by a movement relative to the said end to reverse the direction of operation of said rollers to enable the wrench to be used as a left-hand or right-hand wrench, and a locking pin or rod in the handle the forward end of which is arranged to engage and lock the said disc from rotation by forward pressure on the handle against spring pressure which returns the rod to unlocked position when the handle is released, whereby when so locked the relative movement of the disc and said end may be secured by holding the handle or nut-socket carrying member and turning the other.

12. A reversible friction wrench comprising a handle and head, a rotatable nut-socket carrying member having an end in said head with friction rollers therebetween to enable the same to be operated as a friction wrench, a disc in the head overlying said end and having means operated by a movement relative to the said end to reverse the direction of operation of said rollers to enable the wrench to be used as a left-hand or right-hand wrench, and a resilient locking member in said end pressing against said disc, the latter having adjacent seating depressions therein for said locking member corresponding to the two working positions of the disc.

13. A reversible friction wrench comprising a handle and head, a rotatable nut-socket carrying member having an end in said head with friction rollers therebetween to enable the same to be operated as a friction wrench, a disc in the head overlying said end and having means operated by a movement relative to the said end to reverse the direction of operation of said rollers to enable the wrench to be used as a left-hand or right-hand wrench, and a resilient locking member in said end pressing against said disc, the latter having adjacent seating depressions therein for said locking member corresponding to the two working positions of the disc, the engaging surfaces of the said seats and locking member prior to seating tending to rotate the said disc to effect complete seating.

14. A wrench comprising a head and a handle secured thereto, a rotor in the head having its axis transverse to the handle and alternate driving and release connections to the head in the oscillation of the handle, a nut-socket carrying shank of the rotor projecting axially therefrom outside the head, and a ball bearing in the axial line of the rotor to receive the pressure from the head to the rotor opposite the shank.

15. A friction wrench comprising a head and a handle therefor, a rotor in the head having a nut-socket carrying shank projecting transversely to the handle from one side of the head, gripping rollers between the rotor and head for alternately driving and releasing same in the operation of the handle for wrench purposes, means for confining the rotor to the head on the shank side thereof, closure means on the opposite side of the head over the rotor, and a bearing ball between said closure means and the rotor in the axial line of the latter to transmit the thrust but permit free relative rotation therebetween.

16. A wrench comprising a handle and a ring-like head secured thereto, a rotor in the head

having a shank projecting from one side of the head and adapted to carry a nut-socket or spanner, means for driving the rotor from the head when the handle is swung in one direction and for releasing it when the handle is swung in the opposite direction, means for closing the side of the head over the end of the rotor opposite the shank, and a bearing ball between said closing means and the effective end of the rotor in the axial line of the latter, whereby the thrust from one to the other may be transmitted, the area of rotational contact between the two is reduced to a minimum and the separation of parts is maintained.

17. A reversible friction drive wrench comprising a head and a handle therefor, a rotor in the head housing a shank projecting therefrom on one side of the head, friction grip rollers between head and rotor to grip the rotor to the head and to release the same for wrenching operations in one direction, a reversing disc-like plate overlying the end of the rotor opposite said shank and having transverse projections to reverse by its limited rotation the gripping and releasing operation of said rollers for wrenching operations in the reverse direction, said plate being centrally pivoted for relatively free rotation in the axial line of the rotor, a ball bearing between said plate and the rotor, and a resilient lock for said plate to hold it in the desired position.

18. A wrench comprising a ring-like head and a handle attached thereto, an annular supporting ring on one side of the head, a cylindrical rotor in the opening of the ring-head having peripheral side-edge engagement with said supporting ring and a shank extending therethrough, the head ring being provided with a series of recesses arranged about the cylindrical portion of the rotor, a pair of rollers in each recess, spring means urging each roller into locking engagement between the cylindrical portion of the rotor and the bottom of the respective recess, a reversing selector disc overlying said recesses, rolls and rotor at the side of said head ring opposite the supporting ring, a ball bearing between the disc and rotor, a series of pins carried by said disc and extending into the recesses between the rollers therein, the oscillation of the disc in either direction resulting in the pins engaging and pushing to non-locking position one roller of each pair, and a cap plate over the reversing disc secured at its periphery to the head ring and having a recess in its inner face to receive the disc and hold it in place with freedom for oscillation for reversing, said reverser disc having a portion extending through said cap plate to be grasped by the hand for so reversing the wrench.

19. A wrench comprising a ring-like head and a handle attached thereto, an annular supporting ring on one side of the head, a cylindrical rotor in the opening of the ring-head having peripheral side-edge engagement with said supporting ring and a shank extending therethrough, the head ring being provided with a series of recesses arranged about the cylindrical portion of the rotor, a pair of rollers in each recess, spring means urging each roller into locking engagement between the cylindrical portion of the rotor and the bottom of the respective recess, a reversing selector disc overlying said recesses, rolls and rotor at the side of said head ring opposite the supporting ring, a friction-reducing and spacing bearing between said disc and rotor at substantially the axial center thereof, a series of pins carried by said

disc and extending into the recesses between the rollers therein, the oscillation of the disc in either direction resulting in the pins engaging and pushing to non-locking position one roller of each pair, the lines of engagement of the pins with the rollers being inside the plane of the axes of each pair of rollers, and a cap plate over the reversing disc secured at its periphery to the head ring and having a recess in its inner face to receive the disc and hold it in place with freedom for oscillation for reversing, said reverser disc having a portion extending through said cap plate to be grasped by the hand for so reversing the wrench.

20. A wrench comprising a ring-like head and a handle attached thereto, an annular supporting ring on one side of the head, a cylindrical rotor in the opening of the ring-head having peripheral side-edge engagement with said supporting ring and a shank extending therethrough, the head ring being provided with a series of recesses arranged about the cylindrical portion of the rotor, a pair of rollers in each recess, spring means urging each roller into locking engagement between the cylindrical portion of the rotor and the bottom of the respective recess, a reversing selector disc overlying said recesses, rolls and rotor at the side of said head ring opposite the supporting ring, a ball bearing between the rotor and the disc on the axial line of the rotor to transmit pressure therebetween and prevent their facial contact and the frictional drag thereof, a series of pins carried by said disc and extending into the recesses between the rollers therein, the oscillation of the disc in either direction resulting in the pins engaging and pushing to non-locking position one roller of each pair, and a cap plate over the reversing disc secured at its periphery to the head ring and having a recess in its inner face to receive the disc and hold it in place with freedom for oscillation for reversing, said reverser disc having a portion extending through said cap plate to be grasped by the hand for so reversing the wrench.

21. A reversible friction sealed-chamber wrench comprising a handle, a head having a transverse socket therein, a cylindrical rotor in said socket having a protruding nut-socket carrying shaft, gripping rollers in said head to clutchingly engage and disengage the rotor for wrench operations, a reversing selector disc over said socket and driven rotor on the opposite side of the head from said shaft to reverse the direction of operation of said clutch rollers, a friction-reducing bearing between said disc and rotor, said head having a cap member over said disc and peripherally secured to the head, the disc having a portion or part projecting through the cap by which the same may be oscillated for reversal of the rollers, a non-metallic seal against the passage of dirt or the like between said cap and said disc, and non-metallic sealing means for sealing the socket around the other side of the rotor and shaft against the passage of foreign matter, whereby a sealed chamber for the mechanism of the wrench is formed in the head.

22. A wrench comprising a ring-like head and a handle attached thereto, an annular supporting ring on one side of the head, a cylindrical rotor in the opening of the ring-head having peripheral side-edge engagement with said supporting ring and a nut-spanner carrying shank extending therethrough, the head ring being provided with a series of recesses arranged about the cylindrical portion of the rotor, a pair of rollers in each recess, spring means urging each

roller into locking engagement between the cylindrical portion of the rotor and the bottom of the respective recess, a reversing selector disc overlying said recesses, rolls and rotor at the side of said head ring opposite the supporting ring, a series of pins carried by said disc and extending into the recesses between the rollers therein, the oscillation of the disc in either direction resulting in the pins engaging and pushing to non-locking position one roller of each pair, a cap plate over the reversing disc secured at its periphery to the head ring and having a recess in its inner face to receive the disc and hold it in place with freedom for oscillation for reversing, said reverser disc having a portion extending through said cap plate to be grasped by the hand for so reversing the wrench, the said head ring, supporting ring and cap plate being tightly secured together against the admission of dirt and moisture, and a dirt and moisture seal between the cap plate and reversing
